José Simeon Oliver
BY ATTORNEYS

UNITED STATES PATENT OFFICE.

JOSE SIMEON OLIVA, OF REGLA-HABANA, CUBA.

CHLOROFORMER.

1,112,312.

Specification of Letters Patent. Patented Sept. 29, 1914.

Application filed December 16, 1913. Serial No. 897,009.

To all whom it may concern:

Be it known that I, Jose SIMEON OLIVA, a citizen of Cuba, and a resident of Regla-Habana, Cuba, have invented a new and Improved Chloroformer, of which the following is a full, clear, and exact description.

My invention relates to a device for the administration of an anesthetic; and the object thereof is to provide a simple, light, efficient and inexpensive device which is sanitary, as it can be easily taken apart and sterilized, which can be easily and quickly attached and removed from the patient, in which the amount of anesthetic administered can be easily regulated, and in which the anesthetic before being administered to the patient is spread over a large area to facilitate the evaporation of the same.

I obtain the above object by providing a nose piece having an extension whereto a removable container for absorbent material is fitted, and with which extension is associated a receptacle for an anesthetic with means for controlling the feed from the same to the said container, said container being provided with an outlet toward the nose piece for the vapors of the anesthetic formed therein by the exposure of the anesthetic to the large surface exposed by the absorbent material.

The invention consists of the construction and combination of parts to be more fully described hereinafter and fully set forth in the claims.

Reference is to be had to the accompanying drawings forming a part of this specification, in which like characters indicate corresponding parts in all the views and in which:

Figure 1 is a perspective view showing an embodiment of my invention in use; Fig. 2 is a longitudinal section of the same; Fig. 3 is a section on line 3—3, Fig. 2; Fig. 4 is a section on line 4—4, Fig. 2; and Fig. 5 is a perspective view of the container for the absorbent material.

Referring to the drawings, 7 represents the nose piece, which is provided with an extension 8, preferably of prismatic cross section, the extension forming properly a continuation of the nose piece, said extension 8 being open at its lower and upper ends; and adjacent the upper opening the said extension is provided with undercut grooves 9 into which is fitted a pair of contacting

slides 10 closing the upper opening. Each

of the slides 10 is provided with a central slot 11 extending from the end to about the middle of the slide, as best shown in Fig. 3. The slots 11 of the upper and lower slide are in alinement, and when the slides are in normal position, covering the upper opening in the extension 8, as shown in Fig. 3, the said slots are at opposite sides of said slides and together form an opening 65 substantially in the center of the extension 8. Engaging the opening formed by 65 two slides 10 with its stem 12 is a receptacle 13, which is supported on the slides by the engagement of the flange portions 70 of the stem with the slides. The said receptacle is adapted to receive the chloroform, or any similar anesthetic, through the plugged opening 14 and to discharge the same through the stem 12 by means of a 75 valve 15 controlling the discharge from the same. The receptacle 13 is preferably made of glass, so as to facilitate the control of the amount of anesthetic to be discharged.

Fitting snugly into the extension 8, 80 through the lower opening, is a container 16 open at its upper end and at the side facing the nose piece the wall of the container is formed of a fine mesh fabric 17. The absorbent material 18 is placed in the 85 container from the upper end before the same is fitted into the extension wherein the upper end of the container comes in engagement with the shoulder at the upper end of the opening of the extension. The 90 position of the container 16 within the extension 8 is substantially central with the receptacle 13, and when the valve 15 is open to allow the anesthetic to flow on to the absorbent material 18 in the container 95 16 the same is rapidly spread over a large area of the absorbent material and thereby facilitates its evaporation; and as the vapors formed have no outlet from the upper end of the extension 8 or from the lower 100 end of the container, the same can only escape through the fabric 17 of the container, which leads to the nose piece. Therefore when the said device is placed on the patient, as shown in Figs. 1 and 2, 105 the gauze or fabric 17 faces the nostrils of the patient, and as he breathes he necessarily inhales the vapors coming through the said fabric.

The device is maintained in proper position about the nose of the patient by providing elastic laces 19 secured to the nose

piece at one end and having at the opposite end ear pieces 20 whereby the said device is properly secured to the patient, as shown in Fig. 1.

5 It is understood that, if desired, the nose piece 7, at its free end, can be padded so as to prevent the unnecessary escape of the anesthetic vapors.

Having thus described my invention, I 10 claim as new and desire to secure by Letters Patent:

1. In a chloroformer, a nose piece having an extension forming a continuation of said nose piece, said extension being open 15 at the top and bottom thereof; slides adapted to close the top opening of the extension; a receptacle for anesthetic engaged by said slides and whereby the same is secured to said extension; a container for absorbent 20 material fitting into said extension through the lower opening, said receptacle having a valve-controlled discharge into said container, said container having a fine mesh wall forming an outlet from said container 25 into said nose piece, said nose piece having means whereby the same can be properly secured and maintained on the patient.

2. In a chloroformer, a nose piece having

an extension, said extension having an opening at the top thereof and under-cut grooves 30 adjacent the opening; two superposing slides fitting into said groove, each of said slides having a longitudinal slot extending substantially to the middle of the same, said slides normally closing the upper opening 35 of said extension; a receptacle for an anesthetic, having a stem engaged by the slots of said slides and whereby said receptacle is secured to said extension; a container for absorbent material within said extension and removably associated therewith, said receptacle having a valve in said stem for controlling the discharge from said receptacle into said container, said container having a fine mesh wall forming an outlet 40 45 therefrom into the nose piece; and resilient means adapted to engage the ears of the patient for maintaining said nose piece in proper position on the patient.

In testimony whereof I have signed my 50 name to this specification in the presence of two subscribing witnesses.

JOSÉ SIMEON OLIVA.
